J. J. HAGGERTY

WRENCH

Filed Nov. 29, 1926

UNITED STATES PATENT OFFICE.

JAMES J. HAGGERTY, OF PORTLAND, OREGON.

WRENCH.

Application filed November 29, 1926. Serial No. 151,483.

This invention relates to tools and more particularly to a wrench of the type including a stationary jaw and a movable jaw slideable towards and away from the stationary jaw and adapted to be releasably held in a set position by engagement with a rack carried by the shank portion of the wrench.

One object of the invention is to provide a wrench of this type in which the movable jaw may be easily adjusted relative to the stationary jaw and securely but releasably held in a set position.

Another object of the invention is to connect the movable jaw with a hand grip carried by the shank of the wrench so that, when the wrench is in use, the hand grip may be firmly grasped and danger of the movable jaw accidentally slipping out of proper spaced relation to the stationary jaw obviated.

Another object of the invention is to permit the movable jaw to have limited tilting movement towards and away from the stationary jaw, when in a set position and the wrench operated similar to a Stillson wrench.

The invention is illustrated in the accompanying drawing, wherein—

Figure 1 is a view showing the wrench principally in side elevation, the hand grip being shown in longitudinal section;

Fig. 2 is a fragmentary view of the wrench showing the movable jaw moved out of engagement with the rack for adjustment relative to the stationary jaw;

Fig. 3 is a transverse sectional view taken on the line 3—3 of Fig. 1, and

Fig. 4 is a transverse sectional view taken on the line 4—4 of Fig. 1.

The wrench constituting the subject-matter of this invention includes a stationary jaw 1, a shank or handle 2 having the stationary jaw projecting transversely from its forward end, a movable jaw 3 and a hand grip 4. The cooperating pipe or nut-engaging faces of the two jaws 1 and 3 are provided with teeth 5 and 6 so that they may have firm gripping engagement with a pipe but if desired they may have smooth faces.

The portion of the shank or handle adjacent the stationary jaw is cut to provide a longitudinally extending rack 7 and the rear portion of the shank has opposite side faces formed with longitudinally extending grooves 8 which constitute guideways, the purpose of which will be hereinafter set

forth. It will thus be seen that the shank and stationary jaw together with the rack 7 constitute a unitary structure which will be very strong and at the same time simple in its construction.

The movable jaw 3 is provided with an elongated body which extends longitudinally of the shank and when in an operative position extends in diverging relation thereto, as shown in Fig. 1, with the rear portion 9 of its inner faces 10 contacting with the adjacent face of the shank. A yoke 11 is carried by the forward portion of the movable jaw and extends in straddling relation to the shank with its arms securely fastened in seats 12 formed in opposite side faces of the movable jaw and its bridge portion 13 extending across the face of the shank provided with the rack 7. The bridge portion of the yoke and adjacent portions of its arms are reduced in width, as clearly shown in Figs. 1 and 2, so that this portion of the yoke may fit between the rack teeth and securely but releasably hold the movable jaw in a set position. It should be further noted that the movable jaw may have a certain amount of rocking movement towards and away from the inner face of the shank 2 when the wrench is in use to loosen or tighten a pipe. Arms or strips 14 are secured in recesses or seats 15 formed in the side faces of the movable jaw adjacent its rear end and project across the shank of the wrench and have their outer ends connected by a pin 16. If desired, a sleeve 17 may be mounted upon the pin or rivet 16 to engage the inner side faces of the arms 14 and prevent the arms from moving towards each other into binding engagement with the shank.

The hand grip 4, by means of which the movable jaw is securely held against accidental movement out of a set position when the wrench is in use is substantially U-shaped in cross section and provided with side leaves 18 which overlie opposite side faces of the shank and carry inwardly extending ribs 19 which fit into the grooves or guideways 8. These ribs serve to hold the hand grip in engagement with the shank and also serve to guide and limit its sliding movement longitudinally of the shank. A spring strip 20 extends longitudinally of the hand grip between the shank 2 and the body portion of the hand grip, as shown in Figs. 1 and 4, and at its rear end is secured to the hand grip by a screw or other suitable

- fastener 21. The forward end portion of the spring strip projects from the hand grip and normally extends in diverging relation to the shank, as shown in Fig. 1. At its 5 forward end the spring strip is rolled to form a sleeve 22 which fits about the sleeve 17 and pin 16, as shown in Fig. 2. Referring to this figure, it will be seen that the spring strip is securely held in engagement 10 with the pin and provides a resilient connection between the hand grip and movable jaw. Therefore, the movable jaw may be shifted from the position shown in Fig. 1 to that shown in Fig. 2 when it is desired to 15 adjust it longitudinally of the shank and when released will be returned to the position shown in Fig. 1 with the bridge portion of its yoke engaging the rack to releasably hold the movable jaw in a set position.
- 20 When the wrench is in use, the movable jaw is shifted to the position shown in Fig. 2 and may then be slid longitudinally of the shank into proper spaced relation thereto for engagement with a pipe, indicated by 25 dotted lines in Fig. 1. When in the adjusted position, the jaws will engage opposite portions of a pipe and if a turning movement is applied to the wrench in an operative direction the movable jaw may swing towards 30 the shank a sufficient distance to effect tight gripping of the pipe without the bridge portion of the yoke moving entirely out of engagement with the rack. When the wrench is swung in an opposite direction, 35 the jaws may slide about the pipe in the usual manner in order to obtain a new grip for further tightening. In view of the fact that the hand grip is firmly grasped by the hand which engages the rear or handle 40 forming portion of the shank the movable jaw will be prevented from having movement longitudinally of the shank out of proper spaced relation to the stationary jaw. It will thus be seen that I have provided a 45 wrench which can be very easily adjusted and will be very effective in operation.

Having thus described the invention, I claim:

1. A wrench comprising a shank, a stationary jaw carried thereby, a rack extending longitudinally of the shank, a movable jaw, means slidably connecting the movable jaw with the shank and engageable with the rack to releasably hold the movable jaw in 55 a set position, a hand grip slidably carried by said shank, and resilient means connecting said hand grip with said movable jaw.
2. A wrench comprising a shank, a stationary jaw carried by said shank, said 60 shank being provided with a rack, a movable jaw disposed at the opposite side of said shank from said rack in operative relation to said stationary jaw, a latching yoke carried by said movable jaw and straddling said shank and adapted to engage said rack
3. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 75
4. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 80
5. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 85
6. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 90
7. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 95
8. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 100
9. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 105
10. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 110
11. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 115
12. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 120
13. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 125
14. A wrench comprising a shank, a stationary jaw carried by said shank, said shank being provided with a rack, a movable jaw disposed at the opposite side of said shank from said rack in operative relation to said stationary jaw, a latching yoke carried by said movable jaw and straddling said shank and adapted to engage said rack 130

faces of said movable jaw and its bridge portion reduced to form a latch bar to engage between the teeth of said rack and releasably hold the movable jaw in a set 5 position, a hand grip slidable longitudinally upon the rear portion of said shank, a resilient strip secured to said hand grip and projecting forwardly therefrom, and arms extending from opposite sides of the 10 rear portion of said movable jaw across said shank and connected with the forward end of said strip.

6. A wrench comprising a stationary jaw, a shank extending therefrom and formed 15 with teeth to provide a longitudinally extending rack upon the opposite side of the shank from the jaw, a movable jaw having a body extending longitudinally of the shank at the side opposite the rack and slid- 20 able towards and away from the stationary jaw, a U-shaped yoke straddling said shank

and having its arms secured to opposite side faces of said movable jaw and its bridge portion reduced to form a latch bar to engage between the teeth of said rack and 25 releasably hold the movable jaw in a set position, a hand grip slidable longitudinally upon the rear portion of said shank, a resilient strip extending between the shank and hand grip and projecting from the forward end of the hand grip, a fastener securing the rear end of the strip to the hand grip adjacent the rear end thereof, arms extending from opposite sides of the rear portion of said movable jaw across the 30 shank, the forward end of said strip being formed into a sleeve, and a pin connecting said arms and extending through said sleeve to connect the arms with the strip.

In testimony whereof I affix my signature.

JAMES J. HAGGERTY. [L.S.]
